UNITED STATES PATENT OFFICE.

GEORGE A. E. JONES, OF NEW LONDON, CONNECTICUT.

ELECTRIC FORGE.

Application filed December 20, 1920. Serial No. 431,999.

My invention relates to a portable apparatus for use in metal working operations in which electric currents of large amperage are passed through rivets or other articles for raising them to the desired high heat or other working temperature.

My invention relates more particularly to electric forges or similar apparatus for passing a heavy electric current through metal for heating the same to forging or welding heat, and in the preferred form shown herewith may be used for riveting together elements of structural steel or iron boilers and for other purposes.

15 My invention consists essentially in a simple, easily operated, efficient apparatus of the kind above described which is of great portability and readily adaptable for rods, rivets or other articles of varying sizes and 20 lengths and heats.

My invention consists, more particularly in the combination of yieldably positioned separately movable electrodes and an adjustable bridging connector or conducting piece 25 near said electrodes, and a source of current having its poles connected to said electrodes respectively; though as shown in the appended claims, the scope of the invention is not so limited, whereby the heating of the 30 required articles is done in series.

My invention consists, also, in the combination, with any suitable means for holding the metal to be operated upon, of suitable connecting devices for passing heavy electric-currents through the same, and means 35 for adjusting the electrodes for receiving articles of different sizes.

Other objects of the invention will appear as the description proceeds; and while herein minute details of the invention are described, the invention is not limited to these, since many and various changes may be made without departing from the scope of the invention as claimed.

45 In the accompanying drawings showing by way of example, two of many possible embodiments of the invention,

Figure 1 shows in perspective an appa-

ratus constructed in accordance with one form of my invention;

50 Fig. 2 is a front elevation of a detail of construction;

Fig. 3 shows a plan of the detail of Fig. 2;

Fig. 4 is a front elevation of a detail of 55 an apparatus constructed in accordance with another form of my invention;

Fig. 5 is a plan of the detail of Fig. 3; and

Fig. 6 shows a diagram of the electrical 60 connections of the apparatus.

The various elements of my improved forge are shown mounted on a rectangular frame 10 comprising horizontal front cross pieces 11 provided with bearing pieces 12 thereon having vertical bearing bores therein. Suitable supporting means are provided for said frame such as floor wheels 15 and a swivel castor 16.

65 A pair of electrode-carrying spindles 17 are slidable in said bores and are provided with foot pedals 18 at the lower ends of said spindles for depressing the spindles, and with collars 19 fast on the intermediate part of the spindles. Coiled springs 20 on said spindles compressed between said collars and the lower bearing pieces 12 hold the spindles yieldably raised. Large cubical metallic electrodes 21 are fixed on the upper 70 ends of said spindles and suitably insulated therefrom.

75 In the form of invention shown in Figs. 1 to 3, an inverted U-shaped bracket 24 disposed above said electrodes has its arms 25 fixed to said frame and provided on the inner face with vertical guides 26 receiving end recesses 27 of a horizontal supporting bar 30 slidable on said guides and carrying a thick bridging connector or conducting piece 31 secured on the under face of and insulated from said bar and disposed over said electrodes 21. A horizontal shaft 32 rotatable in bearing brackets fixed on said arms 25 carries a crank handle 33 and pinions 34, the latter engaging vertical racks 35 secured to the ends of said bar 30, whereby rotation 80 of the crank 33 may adjust the height of said

bridging connector or conducting piece 31 in order to receive rivets 38 or other articles of different length between said conducting bar 31 and electrodes 21, against the pressure of said springs 20.

A transformer 40 mounted in the lower part of said frame comprises a primary coil 41 (Fig. 6) and a heavy secondary coil 42 having heavy flexible conductors 43 connecting the ends of said primary coil to said electrodes 21 respectively. A plurality of switch contacts 44 (Fig. 1) are electrically connected to points in said primary coil; and a pivoted switch blade 45 is adapted to engage any one of said contacts. A suitable source of current 46 has one pole 47 connected to said blade 45 and the other pole 48 connected to one end 49 of said primary coil 41.

20 In the form of invention shown in Figs. 4 and 5, the inverted U-shaped bracket 54 has its yoke 55 provided with openings near the ends thereof. Bearing brackets 56 and 57 are fixed on said yoke, the former being provided with horizontal bearing openings 58 and the latter with vertical bearing bores 59, the latter registering with said openings of the yoke 55. Vertical spindles 60 are disposed in said vertical bores 59 and have 25 threaded lower portions 61 and are held against upward displacement by collars 62 engaging under said yoke. Worm wheels 65 (Fig. 4) are provided on the upper end of said spindles and rest on said bearing brackets 57. The horizontal supporting bar 66 provided with threaded end openings 67 received on the threaded portion 61 of said spindles, carries the bridging connector or conducting piece 31 secured to and insulated 30 from its under face. A horizontal shaft 68 in said horizontal bearing openings 58 carries a crank handle 69, and worms 70 engaging said worm wheels 65, whereby rotation of the crank 69 may vertically adjust the height of said bridging connector 31, in order to receive the rivets or other articles of different lengths.

In operating the apparatus the conducting piece 31 is adjusted to the height of the rivet 50 or other metal piece by means of the crank handle so that the rivet may be in contact with the bridging connector or conducting piece 31 under a moderate pressure. The foot pedals are then pressed one at a time 55 and the rivet inserted as shown in Fig. 1 before the pedal is released. The switch is then closed with the blade 45 engaging the right contact 44 to put on the right amount of current, which, passing through one electrode, one rivet, the bridging connector 31, the other rivet and other electrode heats the rivets to the required temperature. The rivet is then grasped with tongs or otherwise and removed as the foot pedal is stepped 60 upon. New rivets may be inserted by the re-

verse operation without cutting off the current. As is well understood in the electric art, many other processes other than the above described may be accomplished by my new apparatus.

Having thus described my invention, I claim:

1. In a rivet heating machine, the combination with a frame, of a transformer mounted in said frame and having an open circuit secondary winding, flexible conductors forming the ends of said secondary winding, two spindles vertically slideable in said frame, an electrode at the upper end of each spindle and connected to the free end of one of said flexible conductors, two vertically extending supports, a vertically extending rack slidably mounted on each support, a support extending upwardly from said frame, a shaft mounted in said frame, a pair of gears on said shaft, each in mesh with one of said racks, a bridging conductor insulated from and secured to said racks and extending horizontally above both of said electrodes, means for actuating said shaft to adjust the position of said bridging conductor, springs for normally maintaining said spindles and electrodes in raised position, foot pedals at the lower ends of said spindles to be engaged to depress said electrodes in opposition to the tension of said springs into position for receiving rivets between the electrodes and said bridging conductor, the springs, when the foot pedals are released, urging the electrodes upward to clamp the rivets between them and the bridging conductor.

2. In a rivet heating machine, the combination with a frame, of a transformer mounted in said frame and having an open circuit secondary winding, flexible conductors forming the ends of said secondary winding, two spindles vertically slideable in said frame, an electrode at the upper end of each spindle and connected to the free end of one of said flexible conductors and having a plane horizontal rivet engaging face, a U-shaped bracket on the top of said frame, a bridging conductor vertically slideable therein, having a plane horizontal rivet engaging face, and extending above the upper ends of said electrodes, means for controlling the vertical position of said bridging conductor, springs for normally maintaining said spindles and electrodes in raised position to clamp rivets between them and the bridging conductor at a position above the upper level of the frame, and means for depressing said spindles in opposition to the tension of said springs to release the rivets disposed between said electrodes and bridging conductor.

3. In a rivet heating machine, the combination with a frame, of a transformer mounted in said frame and having an open circuit secondary winding, flexible conduction

tors forming the ends of said secondary winding, two spindles vertically slidable in said frame, an electrode at the upper end of each spindle and connected to the free end 5 of one of said flexible conductors and having an upper plane horizontal rivet engaging face, a bridging conductor slidably mounted in a vertical direction on said frame above the upper ends of said electrodes and having 10 a lower plane horizontal rivet engaging face,

springs for normally maintaining said spindles and electrodes in raised position to clamp rivets between them and the bridging conductor, means for depressing said spindles to release the rivets anchored between 15 said electrodes and said bridging conductor, and means for adjusting the position of said bridging conductor relative to said electrodes.

GEORGE A. E. JONES.
